SUMP VAULT COVER

Louis A. Scholz, Rte. 32, Sykesville, Md.

Filed June 22, 1960, Ser. No. 61,076

Term of patent 14 years

(Cl. D60—2)

FIG. 1.

FIG. 2.

FIG. 3.

The FIGURE 1 is a perspective view of sump vault cover showing my new design.

The FIGURE 2 is a perspective view thereof with one half of the cover omitted to better show the configurational details thereof.

The FIGURE 3 is a bottom perspective thereof as shown in FIGURE 2.

I claim:

The ornamental design for a sump vault cover, substantially as shown.
